UNITED STATES PATENT OFFICE.

STRAUD K. WOOD, OF HUTCHINSON, KANSAS.

CAR-IDENTIFYING APPLIANCE.

Application filed March 21, 1927. Serial No. 177,114.

This invention relates to a motor car identifying appliance of that class comprising a State or other license certificate readable through a glass plate, and with the latter, contained in a casing to be mounted on a car, the casing being composed of two members slidably fitted together, and the appliance being characterized by the impracticability of removing the certificate without breaking or cutting the plate or destroying or mutilating the certificate, and this being true irrespective of whether the appliance is in operative position on the car or not.

My object is to produce a device of the class mentioned which involves the use of a key having the dual function of locking the members of the casing together as regards slideable movement thereof and of destroying the certificate upon being withdrawn to permit the casing members to be slid out of engagement.

With the above fundamental object in view, the invention consists in certain novel and useful features of construction and combinations of parts as hereinafter described and claimed; and in order that it may be fully understood, reference is to be had to the accompanying drawing, in which:

Figure 1 is a front view of a car identifying appliance embodying the invention.

Figure 2 is a central vertical section of the same.

Figure 3 is a central horizontal section of the same.

Figure 4 is a fragmentary perspective view of the appliance, the view being from the rear and as though Figure 3 had been rotated on a horizontal axis to bring its rear side into view.

Figure 5 is a detail perspective view of a key forming a part of the appliance.

Referring to the drawing in detail, 1 indicates the back member, the same being generally of rectangular form and made from sheet steel or other suitable metal, the top edge of the member being formed at its front side with a downwardly opening hook 2. About midway the height of said member, it is formed with a pair of outwardly projecting perforated ears 3 which initially project a slight distance beyond the side margins of the member, and one of the ears is slotted as at 4 from the perforation outward, for a purpose which hereinafter appears. In order that said ears may be

spaced rearwardly in a plane back of the body portion of the member, the latter in the plane of the upper and lower edges of the ears is formed with incisions 5, the portion between the incisions and forming a continuation of the ears as shown most clearly by Figures 3 and 4, being pressed back at their junction with the body portion as at 6.

In the horizontal plane of the ears 3 and between the same, the body portion is cut vertically near one of the ears and from said cut nearly to the ear at the opposite side, is pressed rearwardly as at 7 to form a horizontal channel, the uncut end of the channel being rounded as at 8 for a purpose which hereinafter appears, it being noted in this connection that the bottom of the channel occupies a vertical plane slightly rearward of the ears 3, and above and below the channel at suitable points the plate 1 is formed with rearwardly projecting bosses 9 of the same depth as the channel, so that when the appliance is pressed against the dash or other suitable part of the car, it will have a firm bearing thereon and thus have no tendency to rock or vibrate and hence produce undesirable noises when the car is in motion.

The front member 10 of the appliance is also preferably made of sheet steel or the like, and conforms substantially in size and contour to the back member. At its side margins it is provided with rearwardly and inwardly disposed hooks 11 for slideable engagement with the side edges of the member 1 forward of the ears 3 thereof, and to limit upward sliding movement of the member 10 upon member 1, and to hold the two members firmly together at their upper and lower edges as well as their side edges, the front member is provided with a rearwardly and upwardly disposed hook 12 at its lower edge for engagement with the lower edge of the back member as the upper edge of the front member enters and engages the hook 2 at the top of the back member. To securely lock the two members together against slideable disengagement, the hooks 11 are provided with notches 13, which when the two members are in operative relation, occupy the horizontal plane of the perforations of the ears 3, and receive the inner edges of the heads 12 of bolts fitted through the perforated ears for securing the appliance in operative position upon the dash or other

part of the car, the heads of the bolts thus making it impossible to slide the two members apart. As hereinafter explained it will be seen that said members are also prevented from being slid apart, by a key hereinafter described, the key cooperating with the heads of the bolts in the function mentioned when the appliance is fastened in place and likewise performing the same function when the appliance is detached from a support and the bolts have been removed.

and the bolts have been removed.

To provide a chamber between the members, the front member is pressed forwardly intermediate its margins to provide a panel 15, and said panel is provided with a large window or opening 16. Before the members are fitted together, a heavy plate of glass 17 or the like, is fitted snugly in said chamber and is provided in its rear face with a horizontal groove or slot 18 extending from a point in the plate contiguous to and laterally beyond the rounded end 8 of channel 7, to or near the opposite edge of the plate, and said channel for practically its full length is 20 bridged by a paper or equivalent license certificate 19, the certificate being fitted against the back of the plate and preferably folded at its upper and lower ends over the upper and lower edges of the plate to not only prevent slippage of the certificate but to also 25 serve between the plate 17 and the back and front members as a buffer and protection against the vibration of the plate and noises incidental thereto.

25 When the plate and certificate have been assembled as explained, a key 20 is slid endwise into the channel 7 back of the certificate, and said key upon encounter with the rounded end 8 of the channel, is bent forwardly under suitable endwise pressure on the key, and caused to perforate the certificate and enter the groove or slot bridged thereby of plate 17, the action being made more effective by forming the advanced end of the key with a narrow extension or tongue 21. This weakens the key so that its advanced end can be more readily bent or deflected and caused to perforate said certificate and enter the groove or slot of the plate 17, and in this connection it should be stated that the key or its extension should be of ductile character so that when unrelieved of pressure against the curved end of channel 7, it shall maintain its bent or deflected relation so that when the key is withdrawn slidingly from the channel, said deflected end or tongue shall travel in the groove or slot and thus tear the certificate for practically its full width. The key at its exposed end beyond the open end of the channel 7 fits flatly against the adjacent ear 3 and is provided with an opening 22 registering with the perforation of such ear, so that the bolt which extends through said ear shall likewise extend through the key and guard

against its accidental or other withdrawal from the channel. When the bolt mentioned is withdrawn, a button hook or pin narrower than the slot 4, can be inserted through the registering openings of said ear and the key and then pulled to slidingly withdraw the key and destroy or mutilate the certificate, such hook or pin being free to pass through the slot 4. Without a hook or pin or the like it would be difficult to withdraw the key when desired, especially if the appliance was still held flatly against the dash or other support by the bolts, as the space, if any, between the back of the key and the dash or other support would be very slight. From the above description and the drawing, it will be apparent that the key tongue or extension not only provides for the mutilation or destruction of the certificate when the key is withdrawn, but it also, by fitting snugly in the groove or slot of the plate 17, serves to lock the two members against slidable movement, as said plate at such a time constitutes in effect a part of the front member, and the channel containing the key is of course a part of the rear member. The key thus has the dual function mentioned.

From the above description, it will be apparent that I have produced a device possessing the features of advantage set forth as desirable in the statement of the objects of the invention, and which may be modified in minor particulars without departing from the spirit and scope of the appended claims. 100

What I claim is:

1. An appliance of the character described, comprising a pair of casing members fitted slidably together and conjointly providing a chamber, the front member having a window opening; a plate fitting in the casing and transparent opposite the window opening and provided with a groove in its rear face, a certificate interposed between the back member of the casing and said plate and bridging said groove in the latter, and a key removably mounted in the casing and projecting through the certificate into said groove. 105 110

2. An appliance characterized as in claim 1, and provided with means engaging one of the casing members and the key to lock the latter against movement. 115

3. An appliance characterized as in claim 1, and in which the key is provided with an opening, and a part extending through a part of the casing and the opening of the key to lock the latter in place. 120

4. An appliance of the character described, comprising a pair of casing members fitted slidably together and conjointly providing a chamber, the front member having a window opening; a plate fitting in the casing and transparent opposite the window opening and provided with a groove in its rear 130

face, a certificate interposed between the back member of the casing and said plate and bridging said groove in the latter, a key projecting into the casing and at a point 5 therein provided with a deflected tongue extending through the certificate and into the groove bridged by said certificate, the rear member proving a guide for compelling the key to travel substantially parallel with the 10 grooved plate when being withdrawn, to insure material mutilation or tearing of the certificate.

5. A car identifying appliance, consisting of casing composed of a pair of members fitting slidably together, the front member having an opening and the back member an internal channel extending transversely with respect to the slidable movement of the members when being fitted together or separated, 15 the channel being rounded at one end and open at the other, a plate fitted between the members and transparent where visible through said window, and provided in its 20

rear side with a groove in the plane of the channel of the back member, a certificate fitting between the back member and said plate and bridging the groove of the latter, and a key fitted for longitudinal slidable movement in the channel of the back member and of ductile character at its advanced end to be 25 caused when such end is pressed against the rounded end of the channel to be deflected 30 forwardly through the certificate and into the groove of said plate.

6. An appliance characterized as in claim 35 5, and provided with means for locking the key to the casing.

7. An appliance characterized as in claim 35 5, and provided with means for locking the two members of the casing against slidable 40 movement and the key to one of the members of the casing.

In witness whereof I hereunto affix my signature.

STRAUD K. WOOD.
